JAR

John F. Dubbs, Lancaster, Pa., assignor to Armstrong Cork Company, Lancaster, Pa., a corporation of Pennsylvania

Filed Apr. 9, 1962, Ser. No. 69,649

Term of patent 14 years

(Cl. D58—25)

FIG. 1.

FIG. 2.

FIG. 1 is a side elevation of a jar showing my new design.

FIG. 2 is a partial cross-sectional view taken along lines 2—2 of FIG. 1.

The dominant features of my design reside in the portions shown in full lines and consist essentially in the band of rounded ribs in the restricted area in combination with the plain shaped bottom, all as shown.

I claim:

The ornamental design for a jar, substantially as shown and described.
